PORTABLE PHOTOCOPY MACHINE

Robert H. Fullerton, St. Paul, Minn., assignor, by
mesne assignments, to International Photo
Copy Inc., St. Paul, Minn., a corporation of
Minnesota

Application May 25, 1938, Serial No. 209,941

24 Claims. (Cl. 88—24)

This invention relates to a portable photocopy machine wherein photocopies may be made in different sizes and with proportioned reductions as well as enlargements, to give a photocopy of the desired size of the article photographed. A feature of this machine resides in a compact unitary structure which is portable and which may be readily taken from place to place and quickly set up to make the desired photographic 10 copies.

A further feature resides in a machine which is self-contained and wherein the supply of photographic paper is provided including means for bringing the paper into exposing position and projecting the paper into the developing tank after it has been exposed, and then carrying the developed paper into the fixing tank. When the machine is set up for use, the developer and fixer tanks are set in the desired position to receive the photographed sheets in quick succession, one after the other. A cutter provides a means for cutting the sheet after it has been exposed and is projected into the developer tank. Thus a roll of sensitized material or paper may be employed in this machine which has a continuous sheet-like form and which is adapted to be fed into exposing position, after which it is carried through the developer and fixing tanks.

A further feature resides in a self-contained portable photocopy machine wherein the same may be folded into a compact state and easily carried. The unit includes a copy board which swings down into operating position extending at right angles and in horizontal position when the machine is ready for operation. Means are provided for adjusting the copy board in relation to the lens and the focal plane so as to give the desired size of reproduction, thus permitting the copy board to be moved up and down in accordance with the scale provided therefor.

A still further feature includes the adjustment in accordance with a scale provided, of the focal plane, thereby providing the two adjustments, primarily of the copy board and the focal plane, the scales of which permit the uniform adjustment of the copy board in relation to the focal plane. The focal plane unit includes the compartment for holding the supply of sensitized paper, together with the ground glass and closure back, and also includes the developer and fixing tanks. When this unit is in operation, the focal plane portion is in upright or perpendicular position, whereas, the developer and fixer tank portions are extended horizontally so that these two portions are at right angles to each other

but are adapted to move in unison. This is an important feature of my invention.

I also provide illuminating means which extend on either side of the copy board when the machine is in operative position and which are individual units so that when they are removed from operating position, they can be placed within the cabinet of the machine. However, when they are placed in operative position they have the necessary electrical connections in the socket which supports them to complete the electric circuit so that they can be illuminated. The cabinet of the machine is wired in a suitable manner to give the necessary source of supply of current to the illuminating units.

It is also a feature to provide a developer tank wherein a perforated sheet engaging means which when set has a tendency of providing a suction against the exposed sheet to adhere the sheet to this perforated means and carry it into the developing tank. This perforated means is of a spiral cylindrical form being rotatable in the developer tank and when the exposed sheet is picked up by the same, it is carried into the developer tank and rotated while adhered to this means, and when developed is projected on through and out of the developer tank so that the developed sheet may be drawn into the fixing tank with the sensitized surface face down. I also provide suitable surface wiping means which cleans the developed sheet of the developer as it is drawn out of the developing tank, leaving the developer in the developer tank and facilitating the fixing of the developed sheet in the fixer tank.

An important feature of my portable photocopy machine resides in the rack means which permits the operation of the copy board or adjustable table which can be called the engineering table or subject holder which is to be photographed, to be moved up and down while it extends right angularly to the main cabinet of the machine, so as to move the same toward or away from the lens. This provides an adjustment, which I believe, is novel in photocopy machines and permits copying of the subject, ranging from a reduction of more than half size to double the size, yet when my machine is made to be confined within a cabinet approximately twenty-eight inches high, eleven inches deep, and fourteen inches wide, I am able to reach the ranges of size as above stated. It is apparent that the machine may be made in any desired size and this is only an example of the flexibility of my portable photocopy machine.

A feature of my machine resides in its light

weight and compact nature. With this structure it is necessary that means be provided for steady-
ing the working parts and to accomplish this I have provided a double pinion operating means 5 on the rack which moves the focal plane unit with the developer and fixing tanks. The racks are carried marginally along the lower surface of the fixing tank, so that when the fixing tank is hinged down into horizontal operating position, the racks engage with the double pinion operating means to operate the focusing of the machine. This means of operation, together with other guiding, supporting and steadyng means, provides the necessary rigidity to the operating 10 parts when the machine is in working position.

My portable photocopy machine is designed to provide a machine having primarily four principal parts, namely, the engineering table or copy board; the camera and casing supporting the 15 racks which operate the engineering board and support the forward portion of the camera bellows; the focal plane unit and cabinet portion supporting the supply of sensitized paper and the ground glass, and the rear portion of the 20 camera bellows; and the developer and fixing tank portions with the inclosing casing portion which are hingedly supported by the focal plane 25 casing portion. These four principal parts of my machine which are co-related together so as to be folded into the cabinet, provide a compact light weight portable machine which can be quickly opened up and set in operative position to make the desired photographic copies of any 30 object placed upon the engineering table or copy board. The machine may be quickly adjusted to make the photographic copies of the desired size. When the machine is not in operation, it may be readily folded together with the developer and fixing 35 tanks containing developer and fixing 40 fluids, if desired. Thus I provide a portable photocopy machine which is self-contained and which may be taken to any place and set up quickly to make the desired photographic copies.

It is also a feature to provide a spring cutter 45 element of a simple construction whereby the sheet of sensitized material coming from the supply roll may be cut off after it is exposed. The spring steel cutter blade automatically adjusts itself in readiness for operation after it has been 50 operated to cut the sensitized sheet.

Further, the lens board and front portion of the bellows to which the lens board is supported, is adjustable vertically so as to raise the position of the lens in the front of the bellows to facilitate 55 the operation of the camera in projecting the images of the articles to be photocopied.

These features together with other details and objects will be fully and clearly pointed out throughout the specification and claims.

60 In the drawings forming part of my specification:

Figure 1 illustrates my portable photocopy machine folded into a compact state within the casing for inclosing the working parts thereof.

65 Figure 2 illustrates my portable photocopy machine opened and in position for operation.

Figure 3 is a vertical cross-section through the portable photocopy machine, showing some of 70 the parts in dotted position and showing the camera bellows folded into the casing with the copy table partially open.

Figure 4 is a section on the line 4—4 of Figure 1, when the casing is closed.

75 Figure 5 is a diagrammatic perspective illus-

tration looking toward the back of the upright portion of the focal plane unit.

Figure 6 is a diagrammatic perspective view of a portion of the focal plane unit, the developer tank portion thereof being removed and the focusing or image receiving glass or means being open, as well as the back being open to disclose the interior portion thereof.

Figure 7 is a diagrammatic perspective view of the developer tank and outer back portion of 10 the focal plane unit, the fixing tank being elevated to show the racks along the bottom of the same and the pinions which operate the racks.

Figure 8 is a diagrammatic perspective of the developer tank, a portion of which is broken 15 away to illustrate the inner end of a portion thereof.

Figure 9 is a diagrammatic perspective detail of a portion of the cutter on the focal plane unit and the operating means for drawing the sensitized sheet or strip into the channel where it is positioned for exposure.

Figure 10 is a transverse cross-section through the developer tank.

Figure 11 is a detail elevation view, looking in 25 from the front of the compartment for holding the roll of sensitized material.

Figure 12 is a section on the line 12—12 of Figure 11.

My portable photocopy machine is designed to 30 provide a device which may be used for making photocopies of objects, or sheets, records, prints, drawings, or any other illustrations which it is desired to photograph at any place where it is wished to set up the machine A. The machine 35 A is a complete unit including the projecting lens 10, bellows 11, focal plane unit 12 having a hinged focusing glass or member 13, the copy board 14 on which the subject to be photographed is adapted to lie, the developer tank 15 and the 40 fixing tank 16, together with a roll or supply of sensitized material 17, so that photographs may be made at any time and place and in rapid succession is desired. With this machine A, copies 45 of valuable papers may be made quickly because the machine may be taken to any place, and in a very short period of time, photographic copies 50 may be taken and completely finished.

The lens 10 and bellows 11 are adapted to be supported at their front portion in the casing portion 18 and the back portion of the bellows 11 is secured within the focal plane portion 12, providing a light-tight compartment through which the lens 10 projects the image to the focal plane unit, and if desired, on the ground glass 55 or focusing element 13. The lens board 10' may be adjusted up and down or vertically by releasing the catch 19 to permit the adjustment of the lens board 10' when it is desired in relation to the copy receiving board 14.

When the machine A is set up for use, the lens 10 and bellows 11 are projected into a position so that the lens 10 is virtually centrally positioned above the copy receiving board 14, and the lens and bellows are fixed in this position. 60 If desired, however, the lens may be moved to the desired position in relation to the copy board 14, but for normal photocopy work I have found that the positioning of the lens in the above manner may be preferable.

The copy board 14 forms the front closure portion for closing the front of the machine A when it is folded together as illustrated in Figure 1. This copy board is adapted to hold the subject B, such as drawings, papers or other objects 70

which are adapted to be photographed, and this board may be provided with lines or gauge marks (not shown in the drawings) to indicate the center of the board or table 14 and to facilitate the easy operation of the machine A in making photographic copies. The table or board 14 is formed with hinged side members 14' which open up as indicated, to enlarge the size of the table 14 for receiving the objects on the same. The table 14 is adjustably supported by the side bars 20 which are formed with longitudinal slots 21 and which are held by the screws 22 positioned in the slots 21 so that the bars 20 may be raised and lowered to adjust the position of the table 14. Each bar 20 is provided with a rack 23 along the inner edge of the same, which is engaged by the pinion 24 as illustrated in Figure 3. The pinions 24 are operated by a shaft which is operated by the hand lever 25 on the outside 20 of the casing portion 18. Thus by operating the handle 25 the table 14 may be raised or lowered. The casing 18 is formed with slots 26 at the top thereof, so that the bars 20 may be operated to move the table 14 close to the lens 10 when desired.

The table 14 with the rack bars 20 may be removed from the casing 18 by removing the screws 22. The machine A may be carried by the handle C which is mounted upon the top of the focal plane unit 12 when the machine is closed, as illustrated in Figure 1.

The focal plane unit 12 is mounted on a series of rollers 27 in the track 28 extending along the bottom of the casing portion 18 so that this focal plane unit 12 may be adjusted to focus the image in the focal plane unit when photographing an object by the lens 10. This adjustment of the focal plane unit is made by operating the handle 29 which may be placed upon the key to operate the rods 30 or 31 as illustrated in Figure 7. The rods 30 and 31 are provided with pinions 32 which mesh with the teeth of the rack bars 33 which are mounted on the bottom of the fixing tank 16. The fixing tank 16 is hingedly supported to the developer tank 15 as indicated in Figure 7. The back portion 34 of the casing of the machine A is adapted to be hinged to the floor portion 35 of the casing portion 18 and is provided with track portions 36 which are extensions of the track portions 28 and adapted to receive the rollers 27. The portion 34 also acts as a tray when opened down into the position illustrated in Figures 2, 3 and 7, so as to receive the fixing tray with the side flange portions 37 of the tray 16 resting upon the guide bars 38 which are fixed along the side of the inside of the casing portion 34, the racks 33 meshing with the pinions 32 when the fixing tray 16 is down into the position illustrated in Figures 2 and 3. The tray casing portion 34 has its end 34' hinged so that it may open out as illustrated in Figure 7, to permit the fixing tray to be moved by the pinions 32 out to project beyond the end of the casing tray portion 34, in focusing the focal unit 12. The fixing tray 16 is provided with a compartment 16' at one end of the same into which the fixing liquid or chemical may be emptied when the tray 16 is elevated in folding the same as illustrated in Figure 7. A closure member 16'' closes this compartment 16' to keep the fixing liquid within the compartment 16' when the machine A is folded, as illustrated in Figure 1, so that the liquid may remain in the fixing tank when the machine A is carried about. When the tray 16 is opened into operating position, the

closure 16'' is opened and the liquid will run into the bottom of the fixing tray.

When the focal plane unit is moved by operating the handle 29, the whole assembly including the upright portion 12 together with the developer and fixing tanks 15 and 16, are moved in the rear portion of the casing of the machine A. The developer tank 12 is provided with side guide bars 39 which operate in the track 40 extending on the inside of the casing portion of 10 the focal plane unit 12 so as to guide the developer tank out into operative position from its inner folded position. It will be apparent that when the machine A is folded, the developer and fixing tanks are moved into the lower casing 18 portion of the focal plane unit 12.

The focal plane unit 12 is provided with a compartment 41 at the top of the same for receiving a roll 17 of sensitized material. The roll 17 is held by the ends 42 of the spool which rest in 20 the bearings 43 to hold the roll 17 rotatable in a manner to permit the sheet of sensitized material 44 to be projected between the fixed roller 45 and the spring urged roller 46. The roller 45 is adapted to be operated by the crank 47 on 25 the outside of the casing of the unit 12 to carry the sensitized sheet 44 through the channel portion 48, in moving the same down into the focal plane. The roller 46 is released against the tension of the spring 49 which permits the end 30 of the sensitized paper or material 44 to be fed between the rollers 45. Then by operating the crank 47 the sensitized sheet 44 is fed into the position to be exposed in the focal plane.

The focal plane proper consists of a channel 35 or space 50 which is formed between the clear glass door 51 and the ground glass door or element 52. The doors 51 and 52 are hinged as illustrated in Figure 6, at one side to permit the opening of the focal plane proper when it is 40 desired for the inspection into the rear portion of the camera of the machine. The doors 51 and 52 are locked in a suitable manner, not illustrated, into closed position so that the sensitized sheet 44 may be extended down through 45 the space 50 between the doors 51 and 52, as illustrated diagrammatically in Figure 9. When the sheet 44 is fed into the space 50, the lower end of the same is passed between the driving roller 53 and the spring urged roller 54 in the 50 bottom of the passage 50 or at the bottom of the hinged members 51 and 52. The roller 54 is mounted on the bottom of the back or closure portion 55 of the focal plane unit 12, so that when the door 55 is closed, the roller 54 will be 55 urged toward the roller 53 to grip the sheet 44 between the same.

The roller 53 is adapted to be driven by the pinion 56 and the gear 57, which in turn is operated by the ratchet 58 and the operating handle 60 59. The handle 59 is positioned on the outside of the casing of the machine, as illustrated in Figure 2.

Thus when the sheet 44 is moved into the space 50 and is engaged by the rollers 53 and 54, 65 by operating the handle 59 through the ratchet 58, the proper amount of the sensitized sheet 44 is brought into position to be exposed in the focal plane unit 12. The focal plane unit, of course, is closed by the door 55 and is light-tight so as to prevent the exposure of the sensitized material 44 until the lens 10 is opened to expose the sheet 44. After the portion of the sheet 44 in the focal plane 12 has been exposed, the handle 59 is operated to drive the exposed 75

portion of the sensitized sheet 44 into the developer tank 15 through the slot 15' in the top of the tank. As the exposed sheet 44 is driven into the developer tank it is engaged by the perforated spiral cylinder 60, which when set by the developer, causes an adhering action to take place on the exposed and entering sheet to hold the exposed sheet against the surface of the cylindrical spiral or drum. The sheet 44 is then 10 cut off by the shear-like operating cutter blade 61, which engages against the complementary cutting edge 62 and which cutter blade is of a spring steel nature and formed to be normally out of the path of travel of the sheet 44 from the rollers 15 53 and 54, as illustrated in Figure 9. The spring cutter 61 is operated by the lever 62 which is hinged at 63 on a fixed portion of the back of the cutter and which causes the lug 64 to press against the link 65 to in turn force the spring 20 arm 66 against the back of the cutter blade 61 to increase the driving force against the blade 61 by the spring tension of the spring lever 66 and cause the same to cut the sheet 44 off. The 25 spring cutter blade 61 is mounted on the back of the cover 55 and the blade extends through the slot 67 close to and directly below the roller 54, so that the sheet 44 is readily cut off.

Then the exposed sheet which has been projected into the spiral drum 60 may be developed 30 by rotating the developer tank handle 68. When the sheet is developed, the handle 68 is rotated in a manner to cause the arm 69 secured to the shaft 70 which the handle 68 operates to rotate the drum 60, to raise the cover 71 on the tank 15 so that the rubber wiper member 72 may be turned from the dotted position illustrated in 35 Figure 8 into the tank 15 by operating the handle 73. Then by reversing the rotation of the shaft 70, the end of the sheet 44 in the developer tank 15 will drop onto the rubber wiper 72, and the rubber wiper 74 under the edge of the cover 71 will come down on top of the sheet 44 by its own weight, and then by engaging the sheet 44, it is pulled between these two members, wiping 45 off the surplus developer liquid on the same and the developed sheet is pulled over the compartment 16' and into the fixing liquid in the tank 16. After the sheet 44 is fixed in the tank 16, it may be removed and dried.

50 In this manner the machine A may be operated to make photographic copies in rapid succession, projecting the sensitized material from the compartment 41 into exposing position, then into the developer tank 15, cut off and developed, 55 and then fixed in the fixing tank 16 so that the operation may be rapid and accurate. With the adjustment of the copy receiving table 14, photocopies may be made, either enlarged or reduced from actual size. Thus these photocopies may 60 be made quickly and economically by my machine A.

The machine A is provided with a pair of illuminating members 75 which are provided with the outer shields and reflectors 76 to throw the light 65 from the same down onto the table 14. The illuminating members 75 are adapted to be supported by the brackets 77 which engage in the sockets 78 formed on the side of the casing as illustrated in Figure 2. The sockets 78 are made 70 so that they will give the proper electrical connection to the illuminating members 75 when the same are supported in the sockets 78. The electric wiring to the illuminating members 75 is not illustrated in the drawings. The illuminating members 75 may be removed from the

78 when it is desired to close the machine A, and it is only necessary to lift the brackets 77 out of the sockets 78 to disengage the illuminating members 75 from the side of the casing of the machine A. When the illuminating members are removed they may be stored inside of the casing of the machine A on either side of the lens 10 and as illustrated in Figure 4.

The features and advantages of my portable photographic machine A have been defined to 10 set forth the construction and operation of the same. A primary advantage of my machine will be readily apparent in that it may be made of any desired size and in the fact that the machine is designed to be self-contained or complete in 15 every detail, including the developing and fixing chemicals which may be carried in the respective tanks when the machine A is moved from place to place. A supply of sensitized photographic material may also be carried at all 20 times in the machine and quickly brought into exposing position so that it will also be apparent that my machine can be used for photographically copying various records, court exhibits, army documents and records, all of which 25 may be accomplished right at the place where such records or exhibits are being used or maintained. Thus it will be apparent that my machine A is entirely complete in itself and may be carried about virtually as easily as a good 30 sized travelling grip, and may be set up very quickly to complete photographic copies of articles whenever desired, and when not in use, may be readily stored away in a small space.

In accordance with the patent statutes I have 35 described the principles of operation and the structural detail of my portable photocopy machine, and while I have shown certain construction and combination of elements in a particular form, the drawings are only illustrative and any 40 variations which may be made by those skilled in the art within the scope of the following claims should be considered as a part of this invention.

I claim:

1. A portable machine for making photocopies including a rectangular folding casing unit, an expandible adjustable copy receiving table; means for adjustably supporting said table; a rear closure for said casing unit, a projecting lens 50 and bellows unit adapted to be extended to a fixed position above said table; a focal plane unit including a compartment for receiving a roll of sensitized material; means for guiding said material into the focal plane in position to receive 55 the image when exposed; and a developer and fixer tank means; means for adjustably moving said focal plane unit with said elements comprising the same over said rear closure; said folding casing inclosing the same to provide a 60 portable carrying case into which said elements are adapted to fold into a compact rectangular state.

2. A portable photocopy machine including an 65 adjustable expandible subject holder; a lens image projecting means; an adjustable focusing plane unit; a foldable track on which said focusing plane unit is adapted to travel, a compartment for a supply of sensitized material 70 upon which the image is adapted to be photographed; a developer and fixing tank means slideable with the focal plane unit on said track; and a sectional-casing means for supporting and inclosing all of said elements to provide a port- 75

able self-contained copy photographing and developing means.

3. A photographing machine comprising a foldable casing adapted to inclose a lens, bellows, focusing element, a developer and fixing tank, said casing being made in sections including front, back and intermediate sectional portions; hinge means for connecting said portions together; rack and pinion means for adjustably holding said front portion in relation to said lens; and foldable track means adapted to permit the adjustment of said focusing element, developer tank and fixing tank in the extended operation of said machine; said casing forming an enclosure to conceal the working parts within said machine.

4. A portable photographing machine comprising a sectional casing including a front closure part, an intermediate lens and bellows supporting part, a second intermediate part adapted to support the sensitized material in the upper portion thereof, a developer tank in the lower portion thereof, and a focal plane having a ground glass for registering an image intermediate the compartment for the sensitized material and said developer tank, and a rear closure part adapted to support the fixing tank therein, hinge means connecting said front closure part and said rear closure part to said intermediate parts of said sectional casing, whereby said casing is adapted to fold into a compact state and inclose all of the parts of said photographing machine.

5. A portable photocopy machine including a casing; a lens and image projecting means; an adjustable focal plane unit having an image reflecting element for focusing said unit; a compartment for a supply of sensitized material; means for projecting the sensitized material from said compartment into exposing position; a developer tank means; an elongated fixing tank means; means for projecting the exposed sensitized material into said developer tank; means for severing the unexposed portion of said sensitized material from the exposed portion; an adjustable subject supporting table to hold the subject being photographed in proper adjusted relation to said adjusted focal plane unit; a casing means for inclosing said elements to provide a portable carrier therefor; and means for foldably supporting said fixing tank, said fixing tank containing liquid sealing means so that said fixing tank may fold into said casing with the fixing chemicals remaining therein.

6. A photographing device including a lens and bellows; a compartment for holding a supply of sensitized material; a focal plane unit associated with said compartment, including a clear glass and a ground glass panel hingedly connected together and adapted to provide a focal plane for the sensitized material; and a closure hingedly supported to and adapted to provide a closing means for the back of said focal plane unit to make the same light-tight.

7. A photographing device including a lens and bellows; a compartment for holding a supply of sensitized material; a focal plane unit associated with said compartment, including a clear and a ground glass hingedly supported and adapted to be positioned in a manner to provide a space therebetween for the sensitized material; a rear closure for said focal plane unit to make the same light-tight; a developer tank below said focal plane unit; a cutter on said closure for said focal plane unit to sever the sensitized material after it has passed through said focal plane

unit; and a fixing tank hingedly connected to said developer tank, whereby said developer and fixing tanks can be folded into said photographing device when the same is closed.

8. A photographing machine including a sectional casing, a front casing section adapted to form the work table; an intermediate lens and bellows supporting casing section; means for horizontally adjustably supporting said front casing section to said intermediate bellows supporting section, a second intermediate casing section adapted to provide a focal plane unit; means for adjusting said focal plane unit in relation to said bellows supporting casing unit, to focus said machine; a compartment for supporting sensitized material carried by said focal plane unit; a rear closure section; track means formed in the bottom of said focal plane casing unit and in said rear closure section; and developer and fixing tank means carried by said track means; said focal plane unit also being adjustable on said track means; and hinge means for connecting said front casing section and said rear casing section to said intermediate sections to permit said sectional casing to be folded into closed position.

9. A portable photocopying machine including a sectional casing for inclosing the same and comprising a front section, an intermediate fixed section, an adjustable intermediate focal plane section, and a rear closure section; means for hingedly connecting said front and rear sections to said fixed section; track means formed in the bottom of said fixed section, and continuing into said rear section; a compartment for sensitized material in the top of said focal plane section; a focusing means for an image in said focal plane section; a developer and fixing tank foldably associated with said focal plane section; means for slidably adjusting said focal plane section and said developer and fixing tanks on said track means; and means for horizontally adjusting said front section when said casing is opened for making photocopies in reduced or enlarged size in said focal plane section.

10. A self-contained photographing machine comprising a lens; a bellows; a focal plane unit; a compartment for sensitized material; a developer tank; a fixing tank; a cutter for severing said sensitized material after it has been exposed; a sectional casing for inclosing said photographing and developer and fixing elements, including a front closure section, an intermediate fixed section, an adjustable section supporting said focal plane unit, and a rear closure section; said front and rear sections being hingedly connected to said fixed section, and said focal plane unit and section, together with said developer and fixing tanks being slidably adjustable as a unit in the bottom of said fixed section and along the inner part of said rear section when said machine is opened; and means for horizontally adjusting said front section in relation to said lens and said focal plane unit for making enlarged and reduced photographs of articles on said front section when it is opened.

11. A portable photocopy machine including a substantially rectangular casing divided vertically into an upright intermediate body portion, a front closure and a back closure, said body portion including a bellows, a lens, a focal plane unit, and a sensitized paper compartment, a developer tank, and a cutting means for severing the sensitized material; means for moving said sensitized paper into said developer tank after

- exposure, hinge means connecting said front and back closures to said upright body portion to mount said closures pivotal into substantially horizontal position, and means on said back closure 5 cooperable with said bellows in open position of said closure to adjustably support the same.
12. A portable photocopy machine including a substantially rectangular casing divided into an upright intermediate body portion, a front closure, and a back closure, said body portion comprising a bellows, a lens, a horizontally movable focal plane unit, a sensitized paper supply compartment, a developer tank, and a fixing tank; 10 said focal plane unit, developer tank, and fixing tank connected for horizontal movement in unison, and means connecting said front and back closures to said upright body portion to mount said closures for pivotal movement down into substantially horizontal position.
13. A portable photocopy machine including a casing, a lens and image projecting means therein; an adjustable focal plane unit therein including a sensitized paper supply compartment, 15 a developer tank, and means for moving said paper along a focal plane from said compartment to said tank; a fixing tank hingedly secured to said focal plane unit pivotal from horizontal operating position to a plane substantially parallel the focal plane, and a copy holder pivotal over the front of said casing.
14. A portable photocopy machine including a casing, a lens and image projecting means therein, an adjustable focal plane unit therein including a sensitized paper supply compartment, 20 a developer tank, and means for moving said paper along a focal plane from said compartment to said tank, a fixing tank pivoted to said focal plane unit, and means in one end of said fixing tank to contain the fixing liquid when said tank is pivoted.
15. A portable photocopy machine including an upright body portion having an opening in one end thereof, a camera supported in said up- 25 right body portion; said camera including a bellows having one end projectable through said opening, a copy holder hingedly secured to one side of said body portion and foldable against said one end of said body portion to act as a closure therefor, and to a position at substantially right angles to said body portion to support copy; a rear closure pivoted to said body portion and foldable from a closing position adjacent said body portion to a position at substantially right 30 angles to said body portion.
16. A portable photocopy machine including an upright body portion having front and rear surfaces, said front surface having an opening therethrough, a camera supported in said body portion including a bellows having a front end projectable through said opening, a copy holder foldable to overlie the front surface of said body portion to act as a closure for said opening, means pivotally connecting said copy holder adjacent the bottom of said body portion to support said copy holder swingable into substantially horizontal copy holding position, a rear closure, means pivotally connecting said rear closure adjacent the bottom of said body portion to 35 support said rear closure swingable into substantially horizontal position.
17. A portable photographic machine comprising a sectional casing having four parts, namely, a bellows and lens supporting part, a front closure therefor forming a work table in open posi- 40
- tion, a focal plane unit, and a rear closure forming a frame element in open position; said focal plane unit including a sensitized paper compartment, a developer tank, and a fixing tank, said fixing tank being slidably supported upon said rear closure in open position.
18. A photographing machine including a two part casing, one of said parts being adjustable relative to the other of said parts, a bellows, focal plane, and lens carried by said two part casing, 45 a pair of closures for said body pivoted in opposed relation to said other body part, said closures pivotal into substantially parallel relation to close said body when said body parts are brought together, one of said closures folding against one of said casing parts, and the other of said closures folding against the other of said casing parts.
19. A photographing machine including a casing having opposed ends, a bellows, a lens, and a focusing element projectable longitudinally from 50 said casing ends, a pivotal closure for one of said casing ends pivotal from closing position to a copy holding position out of the path of movement of said bellows, a second closure pivoted to said casing and pivotal from closing position over the other of said casing ends to a position parallel the direction of movement of said bellows and focusing element, and cooperable means on said focusing element and said second closure to support said focusing element during adjustment thereof longitudinally of said casing.
20. A photographing machine including a camera having a casing, a prism lens and bellows secured to said casing, said casing having an opening in one end through which one end of said bellows and said lens may be projected in a straight line path, and a closure for said one casing end pivoted to said casing, said closure pivotal from a position closing said end and concealing said opening to a copy holding position out of the path of movement of said bellows and lens when the bellows and lens are projected through said opening.
21. A photographing machine including a casing having an opening in one end thereof, a prism lens and bellows supported by said casing, the end of said bellows supporting said lens being projectable through said opening along a straight line path, and a closure pivoted to said casing and pivotal from a closing position closing said one end to a copy holding position substantially parallel to the path of movement of said bellows and lens.
22. A portable photocopy machine including a casing, a lens and image projecting means therein; an adjustable focal plane unit therein cooperating with said lens and image projecting means, a developer tank movable with said focal plane unit, a fixing tank projecting out of said casing when in horizontal position hingedly secured to said focal plane unit and movable therewith, and pivotal from substantially horizontal operating position to a plane substantially parallel said focal plane, and a closure on said casing enclosing said fixing tank when pivoted parallel to said focal plane unit.
23. A photographing machine including a casing having an opening in one end thereof, a bellows and prism lens supported by said casing and projectable through said opening, a closure pivotal from a position closing said one end to a copy holding position substantially parallel to the line of movement of said bellows and lens, and means pivotally and slidably supporting said closure to

adjustably support said closure in copy holding position movable forward or away from said prism lens.

body portion to swing into horizontal position, means pivotally mounting said front portion to said body portion to swing down into horizontal copy holding position, said camera means in said body portion projectable over said front closure 5 when this closure is in horizontal position, and means vertically adjustably connecting said pivotal mounting means for said front portion to said body portion.

ROBERT H. FULLERTON. 10

24. A portable photocopy machine including a casing having an upright central body portion having an opening in the front thereof, a bellows on said body portion projectable through said opening, a front closure for said body portion acting as a copy holder, and a rear closure, means pivotally connecting said rear portion to said
